CLEANING ADAPTER FOR A JET HYPODERMIC INJECTION DEVICE

Benjamin Kittner, Fair Lawn, N.J., assignor to Vernitron
Medical Products Inc., Carlstadt, N.J.

Filed June 1, 1971, Ser. No. 149,102

Term of patent 14 years

Int. Cl. D24—02

U.S. Cl. D83—12

FIG. 1

FIG. 2

FIG. 3

FIG. 4

FIG. 1 is a perspective view of my new design for a cleaning adapter for a jet hypodermic injection device; FIG. 2 is a front elevational view thereof; FIG. 3 is a rear elevational view thereof; and FIG. 4 is a side view thereof.

The side opposite that shown is a mirror image of the side that is shown.

I claim:

The ornamental design for a cleaning adapter for a jet hypodermic injection device, substantially as shown and described.
